GOODRICH Q. LEWIS, OF WHEATON, ILLINOIS, ASSIGNOR TO WILLIAM H. MINER, OF CHAZY, NEW YORK.

CAR-UNDERFRAME REINFORCEMENT.

1,372,706.

Specification of Letters Patent. Patented Mar. 29, 1921.

Application filed November 28, 1919. Serial No. 340,964.

To all whom it may concern:

Be it known that I, GOODRICH Q. LEWIS, a citizen of United States, residing at Wheaton, in the county of DuPage and State of Illinois, have invented a certain new and useful Improvement in Car-Underframe Reinforcements, of which the following is a full, clear, concise, and exact description, reference being had to the accompanying drawings, forming a part of this specification.

This invention relates to improvements in car underframe reinforcements.

As is well known, there are many designs of cars in use on the railways of the United States and Canada having wooden underframes that are wholly inadequate for the present day heavy service. It is highly desirable to utilize as much of the strength as possible of said wooden underframes in repairing such cars so as to enable them to withstand the present service conditions since this serves to minimize the cost of repair as well as minimizing the time which the cars are kept out of service. It is also highly desirable, in reinforcing such wooden underframe cars, not to expend any metal unnecessarily or, stated in another manner, to utilize all reinforcements with the utmost economy in order to keep down the cost of reinforcements.

The object of my invention is to provide an extremely economical reinforcement for cars having wood underframes, the reinforcement being so arranged that the metal is distributed most effectively to maintain the fiber stresses at all points well within safe working limits and without using any unnecessary metal at those points not subjected to as heavy loads as are certain other points. The invention furthermore contemplates a reinforcement of the character indicated which will permit of access to the king pin at the top bolster without in any wise detracting from the strength or effectiveness of the reinforcement.

In the drawing forming a part of this specification, Figure 1 is a vertical longitudinal sectional view of a portion of a rail-way car underframe and body bolster showing my improvements in connection therewith. And Figs. 2, 3 and 4 are vertical transverse sectional views, upon an enlarged scale, corresponding substantially to the lines 2-2, 3-3 and 4-4 respectively of

Fig. 1. In said drawing, 10-10 denote wood center sills of a railway car underframe, the same being spaced apart the usual distance for underframes of this type. Said center sills 10 will extend from end to end of the car and at each end will abut an end sill 11. The floor boards of the car are indicated at 12, the end wall at 13 and the buffer block at 14. As customary in cars of this construction, the center sills 10 will pass over the tops of the body bolsters, one of the latter being indicated in the drawing at A, the same being of the built-up type although bolsters of other characters may be employed, as will be understood by those skilled in the art. Between the bolsters and abutting the latter, are wood sub-sills. Said sub-sills and center sills 10 are secured together by sill bolts 16 and forwardly of the bolster, the center sills are secured to the draft sills by additional shorter sill bolts 17.

Cars having the wood type of underframe as originally built employ wood draft sills between the bolster and the end of the car, said wood draft sills being located beneath the center sills and secured thereto by sill bolts. Such wood draft sills have proven wholly inadequate for the heavier service now demanded of the cars and it has been found necessary to substitute metal draft sills. In carrying out my invention, I provide such metal draft sills in the form of two vertically extending plates B-B, the same being secured to the inner faces of the center sills 10 and extending down below the latter in order to provide for the attachment of the front and rear stop lugs 18 and 19 at the proper level to correspond with the center line of draft of the draft rigging. The drawbar 20 and yoke 21 of such draft rigging are indicated diagrammatically by the dotted lines in Fig. 1. Each of said plates B has its upper edge extending approximately to the top of the corresponding center sill 10 and the upper part of each plate B will extend from the end sill 11 to a point well in the rear of the bolster as indicated at 22. Forwardly of the bolster, each plate B is extended downwardly as hereinbefore described, such downward extensions being indicated by the reference 23 and the rear edges of the latter will terminate against the forward side of the bolster A.

In order to obtain the necessary rigidity

against bending, buckling, or spreading, forwardly of the bolster, the depending extensions 23 of the plates B are reinforced by upper angles 24 and lower angles 25. Said 5 upper angles 24 are fitted against the under sides of the center sills 10 and bolted to the latter by the bolts 17 and are also riveted to the plates B as indicated by the reference 26. The lower angles 25 extend along the lower 10 edges of the plates B and are riveted thereto as indicated by the reference 27. The rear end of each depending section 23 is braced against the bolster A by an angle plate 28 as most clearly indicated in Fig. 3.

15 Secured to the upper edge of each plate B is a relatively light angle iron 29 which extends from the end sill 11 to the rear end of the plate B, it being understood that the angle 29 and plate B are riveted at intervals 20 throughout their length. At their forward ends, the plates B and angles 29 are secured together and a solid abutment provided against the inner side of the end sill 11 by means of a transversely extending plate 30 25 having side flanges 31 riveted to said angle irons and the plates B.

Also secured to the inner faces of the plates B, directly on top of the bolster A, are angles 32 which extend forwardly of the 30 bolster to a point up to or partly overlapping the rear stop lugs 19. The rear ends of said angles 32 are extended rearwardly of the bolster A to a point approximately one-half way to the rear end of the rearward 35 extension of the plate A. To further tie the plates B with the bolster A, two transversely extending plates 33 and 34 are provided, one directly forward and in engagement with the front side of the bolster A 40 and the other rearwardly of and in direct engagement with the rear side of the bolster A, it being understood that the plates 33 and 34 are riveted to the horizontally extending flanges of the angles 32. Rearwardly of the 45 plate 34, the plates B have their lower sections thereof turned outwardly and interposed between the sub-sills 15 and center sills 10 as indicated at 35, the upper surfaces of the sub-sills 15 being cut away a distance 50 equal to the thickness of the plate 35 to permit of this construction.

From the preceding description, it will be seen that with the construction so far described, the plates B are reinforced forwardly of the bolster against lateral bending or buckling by the three angles 24, 25 and 29 in addition to the stop lugs 18 and 19. This is sufficient to take care of any 55 horizontal bending or buckling forces and, 60 on account of the relatively great depth of the plates B, forwardly of the bolster, sufficient strength is present to prevent any upward bending or buckling of the plates B due to the eccentric application of the load 65 from the draft rigging. Over the bolster,

it is apparent that the reinforcing strength of the angles 24 and 25 is fully compensated for by the angles 32 and the outturned flanges 35 of the plates B, rearwardly of the bolster. There is, however, a critical area 70 in the reinforcement directly above the bolster due to the eccentric application of the load from the draft rigging, the center line of which is below the top of the bolster. This eccentric application of the load, under 75 buffing stress, tends to buckle the plates B upwardly at points approximately in line with the forward side of the bolster A. The load imposed on the plates B at the points mentioned represents the sum due to the 80 direct compression occasioned by the buffing shock plus the additional compression induced in the metal because of the eccentric loading. The greatest stresses in the reinforcement will obviously be those of compression above mentioned, immediately adjacent the top of the bolster and in order that the fiber stress may be maintained within safe working limits at points over the bolster, I employ supplemental, channel-shaped, short, preferably pressed plates C—C which are fitted within the angles 29 and 32 and securely riveted thereto and to the plates B. The supplemental plates C are made comparatively short and extend 85 relatively short distances forwardly and rearwardly of the bolster. With this construction, it is evident that I obtain a relatively large sectional area of metal in any 90 vertical plane passing through the bolster 100 in the plates B, angles 29 and 32 and plates C and furthermore, by making the plates C of channel form, the moment of inertia of the section is made relatively great and the fiber stress thereby reduced within 105 safe working limits.

By employing the arrangement shown, relatively light angles 29 may be employed as is also true of the angles 32. The plates C may also be made of comparatively thin 110 metal and it will be noted that none of the metal is wasted at points forwardly of the bolster where there is sufficient inherent strength in the plates B themselves to take care of any of the stresses which occur at 115 points forwardly of the bolster. It will also be noted that, with the construction shown, the king pin which must be inserted through the top of the bolster A, is readily accessible, inasmuch as the carman is enabled to pass 120 his hand upwardly between the flanges of the angles 32 and the lower flanges of the plates C. In actual practice, I have found that, assuming a buffing force on the center line of draft of the shock absorbing mechanism of two hundred and fifty thousand pounds and the center line of gravity of the section above the bolster as $4\frac{1}{4}$ " above the top of the bolster and $8\frac{1}{4}$ " above the center line of draft, the fiber stresses may be kept 130

less than fifty-five thousand pounds per square inch where plates B of $\frac{5}{16}$ " thickness are used, angles 29 and 32 of $3\frac{1}{2}$ " x $3\frac{1}{2}$ " x $\frac{5}{16}$ ", and plates C of $\frac{3}{8}$ " metal. To economize on material, I form the plates 33 and 34 from those parts of the plates B which would otherwise be wasted where the plates B are cut away at their lower edges at points in the rear of the bolster A so that an exceedingly economical reinforcement is obtained as well as one possessing the necessary strength to withstand present service conditions.

I claim:

- 15 1. In a car having an underframe including wood center sills, a bolster, and an end sill; means for reinforcing said underframe comprising, a vertical plate secured on the inner side of each of said center sills and extending from the end sill over and to a point at the rear of said bolster and having a portion depending below said center sill between the end sill and bolster forming a draft sill, horizontally flanged strengthening elements secured to the outer sides of the draft sill portions of said plates and extending between the end sill and the bolster, relatively light, horizontally flanged strengthening elements secured to the inner faces of said plates along their upper edges and extending from the end sill to points at the rear of the bolster, relatively light inwardly horizontally flanged strengthening elements secured to the inner faces of said plates along the top line of the bolster and extending to the front and rear of the bolster, and a relatively short strengthening element located over the bolster secured to each plate on the inner sides of parts of said 40 strengthening elements secured to the inner faces of said plates, each of said short elements having a vertical section and a horizontally extending flange at its lower edge adjacent the top of the bolster whereby the 45 greatest strength in the reinforcement is obtained over the bolster where the greatest load is imposed.
2. In a car having an underframe including wood center sills, a bolster and an end sill; means for reinforcing said underframe comprising, a vertical plate secured on the inner side of each of said center sills extending from said end sill over and to a point

in the rear of said bolster and having a portion depending below said center sills between the end sill and the bolster forming a draft sill; horizontally flanged strengthening elements secured to the outer sides of the draft sill portions of said plates extending between the end sill and the bolster; relatively light angle irons secured to the inner faces of said plates along their upper edges and extending from the end sill to points at the rear of the bolster; relatively light angle irons secured to the inner faces of said plates along the top line of the bolster and extending to the front and rear of the bolster; and a relatively short channel-shaped plate, disposed over the bolster, secured to the inner side of each of said first mentioned plates on top of the vertical flanges of said angle irons.

3. In a car underframe, the combination with an end sill, a bolster, a center sill extending over the bolster and abutting the end sill, and a sub-sill terminating at the rear side of the bolster; of a reinforcing vertically extending plate secured to the inner face of said center sill, the upper part of said plate extending from the end sill to a point at the rear of the bolster, said plate having a depending section forwardly of the bolster adapted to serve as a draft sill, the rear end of said depending section abutting the forward side of the bolster, said plate having an outturned flange along its lower edge rearwardly of the bolster and interposed between the center sill and sub-sill; of upper and lower angle irons secured to the outer side of said depending section of the plate and extending from the bolster to the end sill; an upper relatively light angle iron secured to the upper portion of the inner face of said plate and extending from the end sill to a point at the rear of the bolster; a relatively light angle iron secured to the inner face of said plate extending over the bolster and disposed immediately above the bolster; and a relatively short, light channel-shaped plate disposed over the bolster and secured to the vertical flanges of said inner angle irons and the plate.

In witness that I claim the foregoing I have hereunto subscribed my name this 20th day of Nov. 1919.

GOODRICH Q. LEWIS.
